UNITED STATES PATENT OFFICE.

THOMAS J. NEACY, OF MILWAUKEE, WISCONSIN, ASSIGNOR TO THE FILER & STOWELL COMPANY, OF SAME PLACE.

LOG-DOGGING APPARATUS.

SPECIFICATION forming part of Letters Patent No. 655,573, dated August 7, 1900.

Application filed March 20, 1899. Serial No. 709,732. (No model.)

To all whom it may concern:

Be it known that I, THOMAS J. NEACY, a citizen of the United States, residing at Milwaukee, in the county of Milwaukee and State of Wisconsin, have invented certain new and useful Improvements in Log-Dogging Apparatus, of which the following is a specification, reference being had to the accompanying drawings, forming a part thereof.

10 This invention relates to dogging apparatus for holding logs while they are cut to length. Its main objects are to rigidly hold a log firmly on both sides of the cut, and thus prevent the severed or partially-severed parts 15 from closing and binding upon the saw, and to insure the effective engagement of the dog-jaws on both sides of the cut in dogging irregular sized or shaped logs.

10 It consists of certain novel features in the 20 construction and arrangement of component parts of the apparatus, as hereinafter particularly described, and pointed out in the claims.

25 In the accompanying drawings like letters designate the same parts in the several figures.

30 Figure 1 is an elevation of my improved log-dogging apparatus, certain parts being broken away and shown in vertical section, the plane of the elevation and section cutting the log-way transversely. Fig. 2 is an elevation and vertical section as viewed from the left with 35 reference to Fig. 1, and Fig. 3 is a perspective view of the equalizing connections between the dog-jaws and the lever by which they are operated.

40 In squaring the ends of logs and sawing them to the desired lengths unless they are firmly held in place on both sides of the saw one part when severed or partially severed 45 from the other is apt to move or settle, so as to crowd against the saw and cause it to bind, thus rendering it difficult to withdraw it from the cut and occasioning annoyance and loss of time. Under such conditions the saw not only works hard, but is liable to buckle and be broken or injured, or damage to other parts of the mill or apparatus or injury to attendants is liable to occur. To avoid the contingency of such troubles and accidents, as well 50 as to secure the attainment of the objects above stated, is the purpose of the construction hereinafter described.

The dogging apparatus embodying my invention is designed for use in connection with a log way or slide in which runs an endless 55 chain provided with dogs for hauling logs into a mill and with a crosscut-saw, commonly called a "drag-saw."

Referring to the drawings, A designates a log way or slide, and B a chain provided with 60 dogs b of the usual or any suitable construction and arrangement for hauling logs into a mill.

C C and C' C' are jaws arranged in pairs on opposite sides of the logway. They are or 65 may be of approximately-triangular shape, as shown in Fig. 1, and they are mounted at their inner lower angles upon shafts D D, which are supported at their ends in boxes 70 d d and serve as pivot or fulcrum bearings for said jaws. The shafts D, arranged underneath and parallel with the logway A, and the boxes d d at each end thereof may be conveniently cast in one piece, as shown in Figs. 1 and 2. The inner upper portions of the 75 jaws are preferably curved to correspond approximately with the shape of logs of varying sizes and are provided with teeth c c to engage with logs and prevent them from slipping or turning when said jaws are closed 80 against them. The boxes d d may be conveniently mounted upon and carried by cross-timbers, as shown.

E is a horizontally-disposed lever arranged underneath and parallel with the jaws C and 85 C' and hinged or fulcrumed at or near one end at e to a suitable support. This lever may be conveniently constructed, as shown in Figs. 2 and 3, of two parallel beams or timbers connected at or near the free or vertically-movable end of the lever by a cross-piece e'. Upon said beams or timbers directly below the pivot or fulcrum shafts D of the dogging-jaws are mounted two parallel equalizing-shafts F F, which are journaled at 90 their ends in boxes f f, attached to said beams. Each of the shafts F is formed or provided with arms or ears f' f', projecting from opposite sides thereof and connected with the two jaws C C or C' C' on one side of the log-way by links or rods G G. Each of the two jaws on either side of the logway is movable upon their common supporting-shaft D independently of the other, so that one of the

jaws may advance or recede relatively to the other.

II is a vertically-disposed cylinder having a piston fitted therein and connected by its 5 rod h and an intermediate link h' with the cross-piece e' of lever E for raising and lowering the same, and thus simultaneously opening and closing the opposing jaws C C'.

I is a pipe for supplying steam or other 10 fluid-actuating medium to said cylinder.

J is a valve for controlling the admission and release of the actuating medium to and from opposite ends of said cylinder, with 15 which it is connected by brauch pipes or passages, as shown in Fig. 1. K is an exhaust-pipe leading out of the lower part of said valve. The valve-stem is connected with a lever L, which extends within convenient 20 reach of the operator in charge of the drag-saw.

The arrangement of the various parts of the apparatus may be varied according to the conditions and requirements of different mills—as, for instance, the cylinder II may be located above the lever E.

The apparatus above described operates as follows: A log being hauled into the mill upon the logway A and stopped in position thereon to be cut off at the desired point, which 30 would lie midway between the jaws C C or C' C' in the plane of the drag-saw, the operator thereupon shifts the lever L into position to admit steam into the lower end of cylinder II and release it from the upper end of said cylinder. The piston being forced upwardly lifts the lever E, which in turn through the equalizing connections hereinbefore described forces the opposing jaws C C' toward each other into engagement with the 35 intervening log. If the log varies abruptly in size or in shape or has a knot or other projection opposite either jaw which would prevent it from advancing as far as the other jaw on the same side of the logway, the equalizing connections will permit or cause one of the jaws to recede while the other advances until they are both forced into effective engagement with the log and the log is firmly 40 grasped and held by the opposing jaws on both sides of the cut to be made by the drag-saw. In this way either part of the log which 45 may not be firmly supported by the logway adjacent to the cross-cut will be prevented from slipping or settling when severed or partially severed from the other part and crowding against the saw, thus interfering with its proper operation, preventing its withdrawal from the cut, and breaking or injuring the saw or other parts of the mill.

60 I claim—

1. In apparatus for dogging logs, the combination with a logway and conveyer, of vertically-disposed pivoted jaws arranged on opposite sides of the logway and movable transversely thereto, a vertically-movable lever 65 connected with said jaws so as to simultaneously close the same upon a log, a cylinder

having a fluid-supply connection provided with a controlling-valve, and a piston fitted in said cylinder and connected with said lever, substantially as and for the purposes set forth. 70

2. In apparatus for dogging logs, the combination with a logway and conveyer of two pairs of opposing jaws arranged in vertical planes on opposite sides of said logway and adapted to grasp a log on opposite sides at different points in its length, and means for simultaneously opening and closing said jaws, substantially as and for the purposes set forth. 75

3. In apparatus for dogging logs, the combination of two pairs of opposing jaws adapted to engage a log on opposite sides and at different points in its length, means for simultaneously closing said jaws against a log, having self-adjusting equalizing connections with said jaws, whereby engagement of both jaws on each side of the log is insured, substantially as and for the purposes set forth. 80

4. In apparatus for dogging logs, the combination with a logway, of two pairs of opposing jaws arranged on opposite sides of and transversely to said logway, two equalizing-shafts each having oppositely-projecting arms which are respectively connected with the two jaws on one side of the logway, and means for moving said equalizing-shafts toward and from said jaws, substantially as and for the purposes set forth. 85

5. In apparatus for dogging logs, the combination with a logway, of two pairs of jaws arranged on opposite sides thereof and movable transversely thereto, equalizing-shafts each having oppositely-projecting arms which are connected with the jaws on one side of said logway, a vertically-movable lever carrying said equalizing-shafts, and means for raising and lowering said lever, substantially as and for the purposes set forth. 90

6. In apparatus for dogging logs, the combination with a logway and conveyer, of two pairs of opposing jaws pivoted at their inner lower portions to a suitable support and movable transversely to said logway, equalizing-shafts arranged below and parallel with the pivot-bearings of said jaws and each having oppositely-projecting arms which are connected by rods with the jaws on one side of the logway outside of their pivot-bearings, a vertically-movable lever carrying said equalizing-shafts, a cylinder provided with a piston which is connected with and arranged to raise and lower said lever, and valve-controlled fluid supply and exhaust connections leading to opposite ends of said cylinder, substantially as and for the purposes set forth. 95

In witness whereof I hereto affix my signature in presence of two witnesses.

THOMAS J. NEACY.
